NILS ERIK WAHLBERG, OF PONTIAC, MICHIGAN, ASSIGNOR TO OAKLAND MOTOR CAR COMPANY, OF PONTIAC, MICHIGAN, A CORPORATION OF MICHIGAN.

MUFFLER-CONTROL LEVER FOR MOTOR-VEHICLES.

1,112,043.

Specification of Letters Patent. Patented Sept. 29, 1914.

Application filed February 24, 1914. Serial No. 820,781.

To all whom it may concern:

Be it known that I, NILS ERIK WAHLBERG, a citizen of the United States of America, residing at Pontiac, in the county of Oakland and State of Michigan, have invented 5 certain new and useful Improvements in Muffler-Control Levers for Motor-Vehicles, of which the following is a specification, reference being had therein to the accompanying drawings.

The invention relates to control levers particularly designed for the operation of the muffler cut-out valve of motor vehicles, and it is the special object of the invention 15 to obtain a construction which may be easily adjusted to the particular vehicle on which it is placed.

In the drawings: Figure 1 is a side elevation of the lever in engagement with its 20 locking plate; Fig. 2 is a perspective view of the upper end of the lever; and Fig. 3 is a cross section showing the manner of adjustment.

A is the cut out valve of a muffler. B 25 is a rod or lever for actuating said valve, which projects upward therefrom through a slot C in a guide plate D and which is provided with an operating cross head E above the plate D and a locking cross head F below said plate, with an intermediate portion G having parallel sides engaging the sides of the slot C. The plate D is provided at one point with a groove or recess H for receiving the cross head F, in which 35 position the valve A is closed, but when the rod is depressed and moved out of engagement with said recess, this will open the valve.

To operate properly the length of the 40 rod B must exactly correspond with the space provided between the plate D and the valve A, but as the former is mounted upon the body of the vehicle (not shown) and the latter upon the chassis frame, there 45 will be variations in this dimension in different cars. If the space is greater than normal this would prevent the locking cross head F from engaging the recess H; and on the other hand, if the space is less than 50 normal the valve will be held open when the portion is in engagement with the recess.

To avoid this difficulty, I have devised a construction in which the length of the rod B may be quickly adjusted to suit the individual car on which it is placed. This con-

sists in forming the rod of two sections B' and B², which have a threaded engagement with each other and consequently may be lengthened and shortened by relative turning. In the normal position of the rod, however, it is held from turning by the engagement of the flattened portion G with the side of the slot C, but above this portion and between the same and the head E is a rounded shank portion I, which may 60 be turned in the slot.

In adjusting the device to the car, the head E is first inserted through the slot C and then turned, while the portion I is engagement with said slot, to a transversely-extending position. The spring J, which closes the valve A, will press the rod upward and hold the flattened portion G in engagement with the slot to prevent turning of the head E when normally operated, 70 but if it is required to adjust the length of the rod, this may be done by depressing the head until the shank I engages the slot, and then turning to screw the section B' upward or downward in relation to the section B². When the adjustment is completed and the rod is released, it will be again pressed upward by the spring so that the portion G will hold it from turning.

What I claim as my invention is:

1. The combination with an automatically closing valve, of an opening device therefore, comprising a rod connected with the valve, a slotted plate through which said rod passes, cross heads on said rod above and below said plate, a portion intermediate said cross heads for engaging the sides of said slot and preventing turning of the rod therein, and a portion between said guide portion and the upper cross head rotatable in said slot when in engagement therewith.

2. The combination with an automatically closing valve, of a rod for opening said valve, a slotted plate through which said rod passes, cross heads on said rod above and below said plate, an intermediate portion for engaging the sides of said slot to hold said rod from turning, and a portion adjacent said intermediate portion rotatable in said slot when in engagement therewith.

3. The combination with an automatically closing valve, of a rod for opening said valve formed in two sections having a threaded engagement with each other permitting of relative longitudinal adjustment,

a slotted guide through which one of said sections passes, cross heads on said section above and below said plate, an intermediate portion for engaging the sides of said slot to prevent rotation of said section therein, and a portion adjacent said intermediate portion rotatable in said slot, permitting of adjustment of said sections.

4. The combination with an automatically closing valve, of an opening device therefore comprising a rod connected with the valve, a slotted plate through which said

rod passes, a cross-head adjacent said plate, a portion adjacent said cross-head for engaging the sides of said slot and preventing 15 turning of the rod therein, and a portion adjacent said guide portion rotatable in said slot when in engagement therewith.

In testimony whereof I affix my signature in presence of two witnesses.

NILS ERIK WAHLBERG.
